Primary Examiner — Michael A. Pratt*Assistant Examiner* — Wendy L Arminio(74) *Attorney, Agent, or Firm* — Lowe Graham Jones PLLC(57) **CLAIM**

The ornamental design for a dispensing top for a bottle, as shown and described.

DESCRIPTION

FIG. 1 is a top isometric view of a dispensing top for a bottle, showing our new design,
 FIG. 2 is a top plan view thereof;
 FIG. 3 is a bottom view thereof;
 FIG. 4 is a front view thereof, the rear, left side, and right side views being identical;
 FIG. 5 is a front cross-sectional view thereof, taken in the direction of line 5-5 in FIG. 2;
 FIG. 6 is a top isometric cross-sectional view thereof, taken in the direction of line 6-6 in FIG. 7, and shown in a position of use in an unclaimed bottle illustrated in broken lines; and,
 FIG. 7 is a top plan view thereof, shown in a position of use in an unclaimed bottle illustrated in broken lines.
 The broken lines in FIGS. 6 and 7 depict environment and form no part of the claimed design.

1 Claim, 4 Drawing Sheets(56)
